UNITED STATES PATENT OFFICE.

JOHN F. NOLAN, OF CHICAGO, ILLINOIS.

MOLDING-MACHINE.

No. 900,117.

Specification of Letters Patent.

Patented Oct. 6, 1908.

Application filed May 20, 1907, Serial No. 374,617. Renewed February 26, 1908. Serial No. 417,818.

To all whom it may concern:

Be it known that I, JOHN F. NOLAN, citizen of the United States, residing at Chicago, in the county of Cook and State of Illinois, have invented certain new and useful Improvements in Molding-Machines, of which the following is a specification.

This invention relates to molding machines, and is particularly an improvement 10 on the invention shown in my U. S. Patent No. 719250, dated January 27, 1903.

In said patent there is shown a vibrating sand plate adapted to contain a bed of sand, with a half core box above the sand plate, 15 and a pneumatic press to force the core box into the sand while the sand plate is being vibrated by mechanical means.

The present invention provides improved 20 means for forcing the core box into the bed of sand, avoiding the use of a gear or frame overhead and also avoiding the use of a plunger or press overhead. Improved means are also provided for tilting or rocking the core box after the cores are molded therein, 25 for the purpose of depositing said box upon a table, where the half cores formed in a similar box can be united.

The invention also provides improved 30 means for placing and supporting the core and vent rods.

The invention is illustrated in the accompanying drawings, in which

Figure 1 is a plan view of the machine. Fig. 2 is a side elevation thereof. Fig. 3 is 35 an end view. Fig. 4 is a detail in section.

The frame of the machine is indicated at 1 having at each side an angle iron track 2 upon which tracks are mounted the wheels or rollers 3 of a vibrating or reciprocating 40 frame or carriage 4. This frame is operated by means of a shaft 5 and eccentric 6 connected to the frame by a rod 7. When the shaft is turned the frame is caused to vibrate or reciprocate in a manner similar to that 45 described in my patent, above referred to.

The sand plate is indicated at 8, and when 50 put in place it rests upon the side bars of the platform, and it is held in position while the machine is in motion by means of the bosses 9 which project through openings in the frame, made to receive them. The sand plate 8 has a series of slots or openings 8^a therethrough which correspond in number and position to the half cores to be molded, 55 and are for the purpose of permitting the insertion of the core and vent rods. When

these rods are to be inserted they are mounted on strips 10 supported by a frame 11 carried or operated by an air cylinder 12 supported by a hanger frame 13 under the vibrating frame 4, in a manner similar to that disclosed in my said patent. When the frame is elevated the core rods are forced through the slots and into the cores.

To lock the strips 9 and hold them firmly 65 in place during the vibration, locking straps 14 are provided, connected by a cross bar 15 at the rear end of the machine and provided with a handle 16. These straps are notched as indicated at 17 and slide in rebates formed 70 in the inner edge of the vibrating frame 4. The straps may be moved to register the notches 17 with the slots in the sand plate, or with the ends of the strips 10, and after the strips are raised into position the straps 75 14 are shifted to bring the solid part thereof under the strips 10, so that they are thereby locked to the sand plate 8 and are thereby lifted with the sand plate, to hold the core rods in place when the core box is removed 80 from the machine. To this end, the strips 10 are grooved on the under side, as indicated at 10^a, to fit over the upper edges of cross pieces 11^a forming part of the frame 11.

The half core box is indicated at 18, having slots 18^a to allow the escape of the surplus sand which works up therethrough, and this core box is carried in a rocking frame 19, by means of laterally-sliding clamps 20 which are mounted on the frame 19 and enter under straps 21 on the back or upper side of the core box. The clamps are so arranged as to hold the face of the core box a slight distance, say one thirty-second of an inch, above the face of the sand plate. This 95 gives a better joint when the cores are joined together, and any sand that adheres to the core box where they are joined, may be removed, after the core box is inverted, by lightly drawing a soft foundry brush across 100 the surface of the half cores. The frame 19 is pivotally mounted by means of arms 22 extending at the end and journaled upon a shaft 23 which extends across the end of the frame and is fixed to the upper ends of 105 rack bars 24 which extend vertically through boxes 25 fixed to the end of the frame 1. These boxes contain pinions 27 and 28 which mesh with the racks, and the racks back against rollers 29 in the boxes. The pinions 28 are idle. The pinions 27 are mounted 110 upon a cross shaft 30 which is provided at

one end with a crank handle 31 whereby it may be turned. The outer ends of the arms 22 have adjustable counter-weights 32, which may be adjusted thereon to properly balance the weight of the core box and associated parts. The weights have studs or trunnions which travel in slots 33 in the arms 22 so that the weights may be rolled from one end to the other of the slots. Mounted upon the frame 19 are pawls 34 arranged to engage ratchets 35 on the shaft 23, for the purpose of preventing swing or rocking of the frame with respect to the shaft.

In order to clamp the half core box 18, and the frame 19, to the sand plate 8, inverted T clamps 36 are provided, the heads of which work through slots 37 in the sand plate and when pressed down and turned will engage under the sand plates and lock the sand plate and frame 19 together. In order to allow this the shaking frame 4 is provided with circular recesses 38 in which the heads of the T clamps extend and in which they may be turned. Springs 39 hold the clamps up out of the way when not in use. The clamps 20 slide in and out laterally to hold or release the half core box 18, and may be fixed by set screws 40 which extend through slots 41 in the clamps. The clamps work under straps 42 secured to the top of the frame 19.

In operation, the sand is first placed on the sand plate to the required depth, and the frame 19, with the core box 18 in place therein, is swung over upon the sand. The frame 4 and sand plate are then vibrated by the means shown, and the core box is pressed down into the sand by turning the crank handle 31 in the proper direction, which pulls down on the rack bars 34 and consequently presses the core box into the sand, the pawls 34 being engaged with the ratchet 35 to prevent turning or lift of the pivoted frame. When the boxes are packed the frame 19 and the sand plate 8 are clamped together by the clamps 36, which are pressed down and given a half turn. The pawls 34 are then released. The rocking frame 19, with the half box 18 and sand plate 8 held thereby, may then be swung up or rocked on the shaft 23 as a pivot and brought over to the opposite side, with the sand plate and core box face upward, and allowed to rest or be received on a table which may be backed up to the end of the machine to receive the same. The core box can then be unclamped and allowed to remain on the table, and afterwards joined to a similar half core box for the purpose of forming the entire core. The strips 10, being locked to the sand plate 8, also lift when the frame is swung over, and are afterwards removed with the sand plate and replaced in position upon their supports 11^a.

The rocking action of the frame which

supports the core box permits speedy and convenient placing or removal thereof, and is much superior to the overhead press and traveler disclosed in my said patent. The idea of forcing the core box into the sand plate while the sand is being vibrated, as disclosed in my former patent, is retained and utilized in the improved form of machine herein claimed. The combination of the swinging or rocking frame carrying a core box, with a vibrating sand plate, may be utilized or embodied in various other modifications or machines differing in detail from the embodiment shown and described herein.

I claim:

1. In a core-molding machine, the combination of a horizontally - vibrating sand plate, a rocking core box adapted to be swung down upon the sand on the plate, and means to press the core box into the sand. 80

2. In a core-molding machine, the combination of a horizontally - vibrating sand plate, a rocking frame pivoted beside the same, a core box held by the frame, and adapted to swing down upon the sand on the plate, and means to apply pressure to the core box, to force the same into the sand. 85

3. In a core-molding machine, the combination of a vibrating sand plate, a frame pivoted beside the plate, a core box mounted on the frame and arranged to swing therewith to and from the sand plate, and a counterweight on the frame, at the opposite side of the pivot to the core box. 95

4. In a core-molding machine, the combination of a supporting frame, a sand plate mounted to vibrate horizontally thereon, a rocking frame pivotally mounted at the end of the supporting frame and carrying a counterbalanced core box arranged to rock over to and from the plate, and clamps for attaching together the rocking frame and the sand plate. 100

5. In a core-molding machine, the combination of a sand plate and a vibrating support therefor, a rocking frame pivoted adjacent the plate, to swing to and from the same, a core box clamped to the frame, and clamps for attaching together the rocking frame and the sand plate. 110

6. In a core-molding machine, the combination of a supporting frame, a sand plate mounted thereon, a shaft extending across one end of the frame and having vertically movable supports, a rocking frame mounted on the shaft, means to prevent swing of the frame, and a core box carried by the rocking frame and arranged to swing therewith upon the sand plate. 120

7. In a core-molding machine, the combination of a supporting frame, a sand plate mounted thereon, a shaft extending across the end of the frame and having ratchets, vertically movable rack bars supporting the shaft, a crank and pinions meshing with the 130

rack bars to raise or lower the same, a rocking frame pivotally mounted on the shaft and having pawls engageable with the ratchet, and a core box carried by the rocking frame and arranged to swing therewith, to and from the sand plate.

8. The combination with a supporting frame and slotted sand plate thereon, of a core box which may be secured upon the sand plate, removable strips fitting in the slots, and means to lock the same to the sand plate when desired.

9. The combination with a supporting

frame and a sand plate thereon, of a rocking frame pivoted at one end of the supporting frame and carrying a core box, and arms projecting from the rocking frame and having adjustable weights thereon, to counterbalance the core box.

In testimony whereof I affix my signature, in presence of two witnesses.
